(57) **CLAIM**

The ornamental design for a connector, as shown and described.

DESCRIPTION

FIG. 1 is a bottom front perspective view of a connector showing our new design;

FIG. 2 is a top rear perspective view thereof;

FIG. 3 is a top front perspective view thereof;

FIG. 4 is a bottom rear perspective view thereof;

FIG. 5 is a front view thereof;

FIG. 6 is a rear view thereof;

FIG. 7 is a top view thereof;

FIG. 8 is bottom view thereof;

FIG. 9 is a side view thereof; and,

FIG. 10 is another side view thereof.

The broken lines show unclaimed environmental portions of the connector and form no part of the claimed design.

1 Claim, 6 Drawing Sheets
